UNITED STATES PATENT OFFICE.

DANIEL KOCH, OF BOSTON, MASSACHUSETTS.

HAT LINING.

Application filed February 20, 1924. Serial No. 693,999.

To all whom it may concern:

Be it known that I, DANIEL KOCH, a citizen of the United States, and resident of Boston, county of Suffolk, State of Massachusetts, have invented an Improvement in Hat Linings, of which the following description, in connection with the accompanying drawing, is a specification, like characters on the drawing representing like parts.

10 This invention relates to hat linings and particularly to hat linings for use in ladies' hats.

One of the objects of the invention is to provide a novel hat lining which has incorporated in the side portion thereof at the rear a length of elastic cord or tape which is secured at its ends to the lining at points which are more widely separated than the normal length of the tape or cord, whereby a 20 short elastic rib is formed on the wall of the lining at the rear of the hat, which will fit under the base of the head and thus firmly retain the hat in place.

My improved hat lining is self-adjusting 25 and will fit heads of various sizes and shapes.

In order to give an understanding of my invention I have illustrated in the drawings a selected embodiment thereof which will now be described after which the novel features will be pointed out in the appended 30 claim.

Fig. 1 is a vertical sectional view of a hat having a lining therein embodying my invention;

35 Fig. 2 is a section on the line 2—2, Fig. 1;

Fig. 3 is an under side perspective view of the hat shown in Fig. 1 with the lining therein.

In the drawings 1 indicates a lady's hat 40 which may have any suitable or usual shape, the front of the hat being at the right in Fig. 1 and the rear at the left.

My improved lining comprises the usual side portion 2 and top or crown portion 3, 45 these two portions being sewed together around the periphery of the crown as shown at 4. The lining is secured to the hat in the usual way by sewing the lower edge 5 of the side portion thereof to the hat.

50 The present improvements consist in forming a fold 6 in the side wall of the lining at the rear of the hat and placing in said fold an elastic cord or tape 7. This fold is preferably retained in shape by 55 stitching the two sides of the fold together as shown at 8 thus making a channel in which

the elastic cord 7 is located. This elastic cord is in its normal unstretched condition considerably shorter than the normal length of the fold and after the cord is inserted 60 the ends 9 thereof are secured to the lining by stitching 10 or in some other suitable way. Inasmuch as the normal length of the tape 7 in its unstretched condition is less than the distance between the ends 65 11 of the fold the result will be that the elastic nature of the cord or tape will bring the points 11 of the lining toward each other thus producing gathers 12 therein.

The result of this construction is that the 70 lining has an elastic rib formed by the fold 6 and tape 7, which extends across the back portion of the lining and which reduces the normal interior dimensions of the lining in the zone where the rib is located.

75 In placing the hat on the head the elastic rib 6 will be drawn down over the back of the head and because of its elasticity it will stretch as necessary to fit over the hair. The elasticity of the tape 7 causes the rib 80 to hug the head tightly at the back and thus to hold the hat securely in place.

There is an advantage in having the elastic portion of the lining at the back of the hat only, for this allows the front part of the hat to rest against the front of the head while at the same time it causes the back of the lining to fit tightly around the back of the head. This holds the hat much more satisfactorily than if the elastic tape extended entirely around the lining.

90 Another advantage inherent in the invention is that it obviates the necessity of making ladies' hats of different sizes as has been commonly done up to the present time. 95 With my invention it is possible to make hats of one size and then to rely upon the lining to give the hat the size required for any person. In fact, with this improved lining the same hat will fit equally well a 100 person having a large head or quantity of hair or a person having bobbed hair.

I claim:

105 The combination with a hat, of a lining therefor having a side portion and top portion, the lower edge of the side portion being secured to the hat, the side portion at the rear of the hat having a fold therein which extends across the latter only, the remainder of the side portion having no fold therein, and an elastic tape or cord located in the fold and normally having a length less than 110

that of the fold, the ends of the cord being secured to the lining on the exterior thereof at the ends of the fold, whereby the fold is gathered in the direction of its length and a short elastic rib is formed on the wall of the lining at the rear of the hat which fits around the rear of the head, the lining at the front and sides of the hat being full

and non-elastic, whereby when the hat is worn the engagement of the elastic rib with the back of the head will cause the front and sides of the hat to fit against the head of the wearer.

In testimony whereof, I have signed my name to this specification.

DANIEL KOCH.
